UNITED STATES PATENT OFFICE.

MAXWELL H. SUSSMAN, OF KEW GARDENS, NEW YORK, ASSIGNOR, BY MESNE ASSIGNMENTS, TO STEEL AND TUBES, INC., OF CLEVELAND, OHIO, A CORPORATION OF OHIO (INCORPORATED IN 1928).

CHUCK FOR TUBING MACHINES.

Application filed August 12, 1927. Serial No. 212,542.

The invention relates to machines for making fancy hollow tubing such as is used in the construction of articles of furniture, lamp standards and similar articles. In many cases it is desirable, principally for purposes of ornamentation, to give a twisted appearance to such tubes, either throughout their entire length or at spaced intervals lengthwise thereof. Heretofore considerable difficulty has been experienced in accomplishing these results, as the work is mostly done by hand, and the operation accordingly requiring a considerable expenditure of time and in many cases being unsatisfactory in its results. The object of the present invention is to provide a novel and simple chuck and associated mechanism, whereby the desired twisted effect may be easily produced in a uniform and highly satisfactory manner on all classes of the indicated tubing regardless of the cross-sectional form thereof. The invention contemplates particularly the provision of a novel and reliable mechanism capable of producing the twisted effect at spaced and predetermined intervals lengthwise of the tube. Other objects will appear from the description hereinafter and the features of novelty will be pointed out in the claims.

In the accompanying drawings, which illustrate examples of the invention without defining its limits, Fig. 1 is a front elevation of a portion of a tubing machine embodying the novel features; Fig. 2 is an end elevation thereof; Fig. 3 is a plan view of the driving and control mechanism for the chuck; Fig. 4 is a sectional elevation approximately on the line 4-4 of Fig. 3; Fig. 5 is a detail sectional view illustrating the chuck; Figs. 6 and 7 are face views of two examples of said chuck, and Fig. 8 shows an example of the work done by the novel chuck.

The tube forming machines whereby the blank is formed into a tube and welded along the seam may be of any conventional type and include any usual or special features; as the tube forming machine itself forms no part of the invention only enough of said machine has been illustrated to clearly show the novel features of the instant device. In the drawings, 10 represents the supporting frame of the tubing machine or more specifically the welding unit thereof, which is supported upon legs 11 and having mounted thereon the usual rollers 12 and 13 and other

instrumentalities utilized in the forming and welding of the tubing; all of the instrumentalities referred to may be of any conventional form and arrangement.

The chuck whereby the twisted effect is imparted to the tubing is generally located at the delivery end of the tube forming machine, although in some cases the chuck and its associated mechanism may take the form of an independent machine. As shown in Fig. 1, a bracket 14 is connected with the frame 10 by bolts or their equivalent 15 and carries a supporting arm 16 on which a cap 17 is fastened by means of bolts or the like 18. The cap 17 includes an axial neck 19 located in axial registry with the path of travel of the tube *a* as it leaves the tubing machine and accommodating a hollow sleeve 20, the bore of which is in alignment with an opening 21, formed in the bracket arm 16 as shown in Fig. 5. The sleeve 20 is fixed in place by means of an annular shoulder 22 and a clamping nut 23 screwed upon the cap-end of said sleeve which is screwthreaded to receive the same as illustrated in Fig. 5; to maintain the sleeve 20 against rotation in the neck 19, a key 24 is located between said sleeve and neck in keyways provided for the accommodation of said key 24. A race ring 25 surrounds the sleeve 20 in surface engagement with the end of the neck 19 and is fixed in place against rotation between said neck and a second annular shoulder 22^a formed on said sleeve 20, as shown in Fig. 5. The ring 25 comprises part of a ball bearing and provides a raceway for balls 26 and a second race ring 27, the latter being suitably connected with a circular supporting plate 28 which includes a bearing surface 29 in rotatable engagement with the sleeve 20; an annular flange 30 extending outwardly from the sleeve 20 at its free end serves to maintain said plate 28 against axial displacement on said sleeve 20 as shown in Fig. 5. The plate 28 carries the grooving rollers 31 whereby grooves *b* are spirally formed on the tubing *a*, an example of which is illustrated in Fig. 8. The rollers 31 are arranged in predetermined groups upon the plate 28 to provide for instance the rectangular chuck of Fig. 6 or the hexagonal chuck of Fig. 7. In any case, the rollers 31 are journaled in forked members 32 forming integral parts of stems 33 extending into bearing blocks 34 so as to be rotatable therein, as

shown in Fig. 5; washers 35 are located upon the stems 33 between the forked members 32 and the bearing blocks 34 and are fixed against relative movement by means of bolts or the like 36. The forked members 32 carry pins 37 which project through the washers 35 into recesses 33^a in the stems 33, as illustrated in Fig. 5 to key said forked members and stems to the washers 35 and to thereby fix 5 the rollers 31 against movement about the axes of said stems 33. The latter at their inner ends, within the blocks 34, are engaged by thrust bearings 38, adjustably controlled by means of set screws 39. The blocks 34 are adjustably mounted in guides 40 on the face of the supporting plate 28 and are fixed in their adjusted positions by lock-screws 41, extending through slots 42, formed in flanges 43 with which the blocks 34 are provided; with 10 this arrangement the blocks 34 and their associated elements are adjustable in radial directions on the plate 28 to selectively vary the positions of the rollers 31 of a given group with respect to each other.

15 For the purpose of causing the group of rollers 31 to travel in operative movements about the tube *a* to form the grooves *b* therein, a sprocket wheel 44 is attached by bolts 45 to the supporting plate 28 so as to have a rotatable bearing upon the neck 19, as indicated in Fig. 5. The sprocket wheel 44 is connected by means of a sprocket chain 46 with a second sprocket wheel 47 fixed upon a worm wheel shaft 48 which is journaled in ball bearings 20 49; the latter are mounted upon a table 50 which in turn is supported upon legs 51, secured to and projecting upwardly from the frame 10 as shown in Fig. 1. The shaft 48 further carries a worm wheel 52 which meshes 40 with a worm 53 fixed upon a worm shaft 54, rotatably mounted in ball bearings 55 suitably supported upon the table 50, conventional thrust bearings 56 being combined with said worm shaft 54 to absorb end thrusts. A clutch member 57 is keyed upon the shaft 54 so as to rotate therewith and is slidable lengthwise thereof for co-operation with a clutch member 58 whereby a gear 59, which is mounted upon a drive shaft 54^a, is connected with 45 and disconnected from the shaft 54 in the manner to be more fully set forth hereinafter; the drive shaft 54^a is journaled in ball bearings 55^a in axial alignment with the worm shaft 54. The gear 59 meshes with an idler 55 gear 60 which in turn is in mesh with a motor gear 61, secured upon the driving shaft of an electric motor 62, depending from the table 51 and comprising the medium whereby motive power is supplied to actuate the mechanism, as will appear more fully further on in the description. The drive shaft 54^a is operatively connected, by means of a coupling 63, with a reducing unit 64 of any conventional type which is suitably mounted upon the table 60, the reducing unit 64 in turn being con-

nected through the medium of a coupling 65 with an intermediate shaft 66; the latter is journaled in bearings 67 mounted upon the table 50 as shown in Fig. 3. The intermediate shaft 66 carries a bevel pinion 68 in mesh with a bevel pinion 69 secured upon a cam shaft 70 rotatably mounted in bearings 71 supported upon the table 50 and being further provided with a clutch operating cam 72; if necessary or desired thrust bearings 73 of conventional type may be located upon the shaft 70 adjacent to the bearings 71 as shown in Fig. 3.

The cam 72 comprises a plurality of cam sections located in spaced relation, the illustrated example showing three such cam sections 72^a, 72^b, 72^c, each consisting of two cam members A and B adjustable relatively to each other and to the base of the cam to vary the action thereof at will. As shown in Fig. 4, the cam base 72 is slotted as indicated at 74 for the accommodation of locking bolts 75, whereby the cam members A and B of each cam section may be adjusted together upon the base 72 or relatively to each other thereon and fixed in any predetermined adjusted positions. A roller 76 is arranged to successively ride upon said cam sections 72^a, 72^b and 72^c and to drop to the surface of the cam plate 72 between said sections and is mounted upon one end of a clutch lever 77 pivoted at 78 upon a standard 79 projecting upwardly from the table 50, as illustrated in Fig. 4; the opposite end of the lever 77 is forked as indicated at 80 to straddle the collar 81 of the clutch member 57, said forked end 80 carrying rollers 82 which ride in an annular groove 83 formed in said collar 81; a spring 84 acts on the lever 77 in a manner to maintain the roller 76 in operative engagement with the active portions of the cam 72.

In the operation of the mechanism, the tube *a* after having passed through the tube forming machine, travels between the rollers 31 and after having been acted on thereby, continues through the bore of the sleeve 20 and opening 21 of the bracket arm 16. Previously the rollers 31 have been adjusted so as to extend at inclinations across the path of the tube *a*, the degree of inclination being predetermined by the twisted effect which it is desired to impart to said tube *a*; this adjustment is accomplished and fixed through the medium of the washers 35 and their associated elements. In some instances, the rollers 31 may be loosely set in the bearing blocks 34 so as to be capable of automatically finding their own operative positions dependent upon the speed of travel of the tube *a* and the speed at which the rollers 31 are caused to travel in a circular path about said tube. In any case the rollers 31, when in action, will form the spiral grooves *b* in the surfaces of the tubes *a* to give the same a twisted appearance, and when not travelling about the axis

of the tube *a* will form continuing grooves extending lengthwise thereof.

The intermittent actuation of the rollers 31, to form the grooves *b* in spaced groups where-
5 by the tubes *a* comprise sections having a twisted appearance, in alternate sequence with sections having the normal or untwisted appearance of the tubes, is accomplished in the following manner:

- 10 Power is transmitted by the motor 62 to the gears 61, 60 and 59, and to the drive shaft 54^a, which in turn operates the reducing unit 64; the operation of the latter causes the intermediate shaft 66, the bevel pinions 68 and 15 69 and the cam shaft 70 to be rotated at a reduced rate of speed and consequently operates the clutch operating cam 72 at the same reduced speed. As long as the roller 76 travels upon the surface of the cam plate 72, the 20 clutch member 57 will remain out of engagement with the clutch member 58 and the worm shaft 54 will accordingly remain at rest; during such periods the rollers 31 accordingly do not travel about the tube *a* but simply ro-
25 tate about their axes without producing the spiral grooves *b* on the travelling tube. As a result of this, the section *c* of the tube has lengthwise grooves formed thereon and other-
30 wise remains unchanged and is not given the twisted appearance. When, however, the roller 76 rides on one of the cam sections 72^a, 72^b or 72^c, the clutch lever 77 will be operated to throw the clutch member 57 into engagement with the clutch member 58 and to there-
35 by transmit rotative motion to the worm shaft 54. The worm gearing 52—53 is thereby brought into operation and causes a rotation of the shaft 48 which in turn, through the medium of the sprocket wheels 47 and sprock-
40 et chain 46, rotates the supporting plate 28 upon the ball bearings 25—26—27 and accordingly moves the rollers 31 in a circular path about the axis of the tube *a*. This operation continues as long as the roller 76 re-
45 mains upon the high portion of any one of the cam sections 72^a, 72^b and 72^c and results in creating a twisted section *d* upon said tube *a*. As soon as the roller 76 drops from the cam section back to the surface of the cam 50 plate 72, the clutch lever 77, under the influence of the spring 84, will be pivotally actuated to shift the clutch member 57 out of engagement with the clutch member 58, so that further actuation of the worm shaft 54 and its associated elements will cease and movement of the rollers 31 about the tube *a* will also stop. This will result in another 55 untwisted section *c* on the tube *a*, as will be clear from the description hereinbefore. As 60 the operation of the mechanism continues, the tube *a* will finally present the appearance of being twisted at spaced intervals and of not being twisted at the points between the twisted sections *d*. The extent of the sections *c* and *d* 65 and their relative locations upon the tube *a*

is predetermined by the adjustment of the cam sections 72^a, 72^b and 72^c, it being understood that the adjustment may be such that the sections *c* and *d* are of equal extent, or that different sections *c* are of varying extent, or that different sections *d* are unequal in extent. The type of the spiral grooves *b* and consequently the appearance of the sections *d* is dependent upon the character and adjustment of the rollers 31 and may be varied in accordance with any predetermined plans. 70

The chuck itself and the mechanism for intermittently operating the same are simple in construction and require no particularly skilled supervision in the performance of their functions. The chuck and its controlling mechanism are reliable and uniform in action and operate automatically once the predetermined adjustments have been made. 80

Various changes in the specific form shown and described may be made within the scope of the claims without departing from the spirit of the invention. 85

I claim:

1. The combination of a chuck for spirally grooving a travelling tube said chuck normally operating lengthwise of said tube, and means for automatically moving said chuck at spaced intervals in a circular path about the axis of said tube. 90

2. The combination of a sleeve for guiding a travelling tube, a supporting member rotatable about the axis of said sleeve, a plurality of grooving rollers carried by said member for spirally grooving said tube, and means for automatically operating said member at spaced intervals to move said rollers in a circular path about the axis of said sleeve. 100

3. The combination of a stationary sleeve for guiding a travelling tube, a supporting member rotatable about the axis of said sleeve, a plurality of bearing blocks adjustably fixed upon said member, forked members mounted in said blocks and adjustable about axes extending radially with respect to the axis of said sleeve, grooving rollers journaled in said forked members for spirally grooving said tube, and mechanism for automatically operating said supporting member at spaced intervals to move said rollers in a circular path about said axis of the sleeve. 110

4. The combination of a rotatable chuck for spirally grooving a travelling tube, said chuck normally operating lengthwise of said tube, driving mechanism for actuating said chuck, and a cam for automatically controlling said mechanism to move said chuck at spaced intervals in a circular path about the axis of said tube. 120

5. The combination of a sleeve for guiding a travelling tube, a supporting member rotatable about the axis of said sleeve, a plurality of grooving rollers carried by said member for spirally grooving said tube, mechanism for operating said chuck, a motor 125

- for driving said mechanism, a clutch whereby said motor and mechanism are connected with and disconnected from each other, and a cam for automatically controlling said clutch 5 in a manner to operate said supporting member at spaced intervals to move said rollers in a circular path about the axis of said guiding sleeve.
6. The combination of a sleeve for guiding 10 a travelling tube, a supporting member rotatable about the axis of said sleeve, a plurality of grooving rollers carried by said member for spirally grooving said tube, a motor, a drive shaft in driving connection 15 with said motor, a second shaft in operative connection with said supporting member, a clutch whereby said two shafts are connected with and disconnected from each other, a controlling cam, a reducing unit operatively connected with said drive shaft and cam whereby the latter is operated at a reduced speed, and a clutch lever controlled by said cam whereby said clutch is operated to cause said supporting member to be actuated at spaced intervals 25 to move said grooving rollers in a circular path about the axis of said guiding sleeve.
7. The combination of a sleeve for guiding 30 a travelling tube, a supporting member rotatable about the axis of said sleeve, a plurality of grooving rollers carried by said member for spirally grooving said tube, a motor, a drive shaft in driving connection with said motor, a worm shaft, a worm-wheel shaft operatively connected with said supporting 35 member, worm gearing connecting said worm shaft and worm wheel shaft, a clutch member slidably mounted on said worm shaft to rotate therewith, a co-operating clutch member fixed on said drive shaft, a reducing unit 40 connected with said drive shaft, a controlling cam operatively connected with said reducing unit and operated thereby at a reduced speed, and a clutch lever controlled by said cam for periodically moving said slidable 45 clutch member into and out of engagement with said co-operating clutch member whereby said supporting member is operated at spaced intervals to move said grooving rollers in circular paths about the axis of said 50 guiding sleeve.
8. The combination of a rotatable chuck 55 for spirally grooving a travelling tube, said chuck normally operating lengthwise of said tube, driving mechanism for actuating said chuck, and a cam for automatically controlling said mechanism to move said chuck at

spaced intervals in a circular path about the axis of said tube, said cam including adjustable sections whereby the intervals between successive operations of said chuck may be varied.

9. The combination of a rotatable chuck for spirally grooving a travelling tube, said chuck normally operating lengthwise of said tube, driving mechanism for actuating said chuck, and a cam for automatically controlling said mechanism to move said chuck at spaced intervals in a circular path about the axis of said tube, said cam including adjustable sections whereby the duration of the periods of operation of said chuck may be varied.

10. The combination of a rotatable chuck for spirally grooving a travelling tube, said chuck normally operating lengthwise of said tube, driving mechanism for actuating said chuck, and a cam for automatically controlling said mechanism to move said chuck at spaced intervals in a circular path about the axis of said tube, said cam including adjustable sections whereby the intervals between successive operations of said chuck may be varied, and the duration of the periods of operation thereof may be adjusted.

11. The combination of a sleeve for guiding a travelling tube, a supporting member rotatable about the axis of said sleeve, a plurality of grooving rollers carried by said member for spirally grooving said tube, a motor, a drive shaft in driving connection with said motor, a second shaft in operative connection with said supporting member, a clutch whereby said two shafts are connected with and disconnected from each other, a controlling cam, a reducing unit operatively connected with said drive shaft and cam whereby the latter is operated at a reduced speed, and a clutch lever controlled by said cam whereby said clutch is operated to cause said supporting member to be actuated at spaced intervals to move said grooving rollers in a circular path about the axis of said guiding sleeve, said controlling cam including active sections arranged to be adjusted to vary the intervals between successive operations of the supporting member and the duration of the periods of operation thereof.

In testimony whereof I have hereunto set my hand.

MAXWELL H. SUSSMAN.
